FLUSHING APPARATUS FOR WATER CLOSET SYSTEMS

Joseph A. Vogel, Wilmington, Del., assignor to
 Joseph A. Vogel Company, Wilmington, Del., a
 corporation of Delaware

Application June 28, 1933, Serial No. 678,046

5 Claims. (Cl. 4—25)

This invention relates to siphon drain devices for use in connection with water closet and other similar water supply systems, whereby the drainage of water from a portion of the system from which water should be drained after a water flush or supply action may be automatically effected.

More particularly the invention relates to a siphon device for water closet systems of the frost-proof type, such as a Vogel frost-proof water closet system, for automatically draining off water remaining in the system after a flushing action and which would be liable to freeze in cold weather or be subject to contamination from any cause. The invention, however, may be embodied in frost-proof drinking fountains, wash sinks, hydrants, and other like water service apparatus having a drain or waste outlet connection with a waste disposal or sewer line and from which it is desirable to drain residual water after each flush or water supply action.

The main object of the invention is to provide a simple, reliable and efficient type of siphon for draining off the water remaining in portions of the system above the frost line and liable to be exposed to freezing temperature or to be subject to contamination with the result of causing damage to the apparatus or fouling of the water in the water supply system.

Another object of the invention is to provide a siphon tube device of novel arrangement, for the automatic siphoning off of residual water remaining in the system above the frost line after a service action, whereby a quick and effective discharge of all water above the frost line will be reliably effected.

Still another object of the invention is to provide an auxiliary valve controlled waste port which will operate to discharge the residual water to the exterior in the event of the amount of residual water being insufficient to create a siphonage discharge action.

Still another object of the invention is to provide an intake or vacuum break element to break siphonage in the event that the bowl should become filled and overflowing.

With these and other objects in view, the invention consists of the features of construction, combination and arrangement of parts, herein-after fully described and claimed, reference being had to the accompanying drawings, in which:—

Fig. 1 is a side elevation showing the application of the invention to a Vogel type of frost-proof water closet.

Fig. 2 is a vertical front-to-rear section through

the water supply and drain valve mechanism thereof on an enlarged scale and showing the application of the invention thereto.

Fig. 3 is a view in rear elevation of the upper portion of the standpipe and showing more particularly the arrangement of the siphon device.

Fig. 4 is a vertical transverse section through the lower portion of the standpipe on a further enlarged scale and more clearly showing certain features of construction.

Fig. 5 is a fragmentary section through the rear portion of the bowl and showing the vacuum relief or break device and drain channel associated therewith.

In the illustrated embodiment of the invention, I have, for purpose of exemplification, shown the same in application to a Vogel frost-proof type of water closet combination, but it is to be understood that the invention is not limited in application in this respect, as it may be used with similar advantages in connection with frost-proof drinking fountains, wash sinks, hydrants, and other water service apparatus for which it is or may be adapted.

Referring now more particularly to the drawings, 1 designates a closet bowl provided at its upper rear portion with an inlet 2 for supply of flush water thereto and having an outlet 3 at its base for connection, in the usual manner, with a waste pipe and trap forming part of a waste disposal or sewage system. In practice the trap (not shown) is designed to be arranged below the frost line, in the use of the closet in exposed places, in order to prevent liability of the freezing of water therein.

Disposed adjacent the top of the bowl and in rear thereof is a valve casing 4 formed with an upper flush chamber 5, a flush discharge outlet 6, and a lower flush chamber or passage 7 having a lateral inflow and outflow connection 8. The flush discharge outlet 6 communicates with the inlet 2 of the bowl while the connection 8 is provided for communication with the water supply tank 9. Extending downwardly from the lower end of the casing is a standpipe or conductor 10 having a water inlet 11 at its lower end for connection with a water service or supply pipe 12 and having a drain outlet 13 above the level of the water inlet 11, for a purpose hereinafter described.

Arranged within the valve casing 5 and the standpipe 10 is a valve stem 14 carrying within the chamber 7 an upper flushing valve 15 movable to alternately open and close communication between the chambers 5 and 7. At its lower

end the valve stem carries a valve 16 controlling the water supply inlet 11 and a valve 17 controlling the drain outlet 13, portions of the valve stem above and below the plane of the drain 5 valve 17 being of openwork construction or provided with ports 18 and 19 to allow water to flow between the pipe 10 above the level of the drain valve and the drain outlet 13 or water inlet 11 in the different positions of the valve members 16 and 17. A spring 20 associated with 10 the upper end of the valve acts, in conjunction with gravity, to maintain the valve device in a position in which valve 16 closes inlet 11, valve 17 is open and connects that part of the pipe 15 10 above the drain valve with the drain outlet 13, and the valve member 15 is open so that chambers 5 and 7 and the closet and tank are in open communication. A forked arm 21 carried by the pivotally mounted closet seat 22 engages 20 under a head 23 fixed to the upper projecting end of the valve stem and operates thereon to lift the valve when the seat is depressed. On depression of the seat the valve stem is raised to close valve 15 and cut off communication between the pipe 10 and the bowl and to move valve 17 to a position in which it closes the drain pipe 13 and simultaneously moves valve 16 to open position, for the upflow of water through 25 the connection 8 from the supply pipe 12 to the tank 9. The tank will thereupon be filled with water and the air therein compressed until the pressure equals or exceeds that in the supply line, at which the flow of water will be automatically cut off. When the seat 22 is released spring 30 20 moves the valve stem downward to close the valve 16 and to open the valve 15 to establish communication between the tank and bowl for the flushing action and to simultaneously open communication between the lower end of the pipe 11 and the drain outlet 15 for the subsequent drainage off of residual water remaining in the flushing connection at the end of the flushing action, as hereinafter described.

My invention provides for use in connection 45 with this or any other type of flushing apparatus in connection with which it may be employed, a siphonage device 24 for the purpose of effecting a rapid siphonage off from the standpipe and parts of the flushing system above the 50 inlet valve of any and all water remaining in the flushing system, in order to avoid any possibility of the freezing or contamination thereof. This siphonage device comprises a looped tube having a short limb 25 and a long limb 26 connected at their upper ends by a return portion 27. The limbs or legs 25 and 26 are arranged in parallel relation to the pipe 10 and the return portion 55 is preferably disposed so as to loop about the connection 8 and to lie at a level above the highest level of the bowl. The short limb 25 extends downwardly from the return portion 27 and communicates at its lower end with the standpipe 10 through a passage 28, at about the level of the drain outlet 13, so that in the closed 60 position of valve 17 both passages 13 and 28 will be closed while in the open position of said valve 17 both of said passages 13 and 28 will be open. The longer or outlet leg 26 of the siphon extends downwardly to a point below the level 65 of the lower end of leg 25 for the discharge of the siphon water therefrom into the ground outside the standpipe or into a suitable outlet connection. The leg 26 is made of such length relative to the leg 25 as to ensure an efficient siphonage action and in practice this leg 26 may

be made of fluted or zig-zag form or otherwise offset or shaped to increase its effective length to a degree greater than the distance between its upper and lower ends in order to further quicken and increase the efficiency of the siphonage 5 action.

It will be understood that in operation the siphonage device, which may be made of copper tubing of suitable gage, is primed for action by the upflow of water through its leg 25 into its leg 26 during the flushing action and that, upon the closing of the valve 16, and cessation of the flushing action, the water remaining trapped in the pipe 10 will be immediately siphoned off through the siphonage device, in order that a sufficient amount of water is present for the siphonage action, so that the standpipe and its connections above the water supply valve will be freed from water liable to freeze or to be contaminated. By this means all liability of freezing of pipes or 10 derangement of parts of the flushing apparatus due to freezing during cold weather, particularly when the parts of the flushing apparatus above the inlet valve are arranged above the frost line, will be prevented in a certain, reliable and efficient manner at all times whenever there is a sufficient amount of residual water present to operate the siphonage discharge device. By this means, also, the flushing apparatus, when not in use, will be kept clear of any water liable to be 15 20 25 fouled by sewage or other contamination.

The drainage connection 13 is provided in order to ensure discharge of any residual water from the standpipe in the event that the amount of water remaining is not sufficient to cause a 35 siphonage action. This outlet 13 communicates through a pipe 29 terminating in an open valve cage 30 in which is arranged a ball valve 31. This valve opens automatically to permit of a drainage action and then closes to seal the drainage connection 13 against the admission of air, water or other foreign substances. This valve 31 operates to close the outlet 13 at all times and particularly when said outlet is not closed by the valve 17, the valve 31 being of such size and weight 45 as to open readily under the pressure of a comparatively small amount of water in the standpipe to effect the discharge of the water. The parts 30 and 31 are in practice preferably covered by a suitable hood 32 in order to shield the same 50 from obstruction or entrance by foreign particles.

In connection with the apparatus I may employ an air intake or vacuum break device 33 to break the vacuum and prevent siphonage in the event that the bowl should become filled and overflowing. This air intake or vacuum break device comprises a tube having one end 34 disposed in the passage 6 and the tube thence extends around part 6 and has its opposite end 35 disposed above a drain channel or vent passage 36 55 formed in the part 2 of the bowl and opening at its upper end through the rim of the bowl and communicating with the top of the body of the bowl below the base of the rim, through which channel or passage 36 any fluid entering said pipe 33 is permitted to discharge back into the bowl instead of upon the exterior thereof. This air intake or vacuum break device may also be used in connection with other similar flushing and water service systems.

From the foregoing description, taken in connection with the drawings, the construction, mode of operation and advantages of my invention will be readily understood and appreciated by those versed in the art without a further and extended 70 75 80 85 90 95 100 105 110 115 120 125 130 135 140 145 150 155 160 165 170 175 180 185 190 195 200 205 210 215 220 225 230 235 240 245 250 255 260 265 270 275 description. As stated, the invention may be used, not only in connection with frost-proof water closets and others where a siphonage discharge action of residual water is required or desirable, but also with frost-proof drinking fountains, wash sinks, hydrants, and other water service apparatus where such a device may be advantageously employed. While the structural organization of the elements herein described and claimed is preferred, it is to be understood that changes in the form, construction and arrangement of parts falling within the scope of the appended claims may be made without departing from the spirit of the invention as set forth therein.

I claim:—

1. In a flushing apparatus for water closet systems having a water inlet valve located in the ground below the frost line, a siphon device having its intake leg connected to the supply line of the system above said valve for draining water from the system above the frost line after a flushing action.
2. In a flushing apparatus for water closet systems having a standpipe and a water supply valve therein located below the level of the bowl, a siphon device having its intake leg connected to the standpipe above the valve for draining water from the system above the level of said valve after a flushing action.
3. In a water closet flushing apparatus closed to the atmosphere, embodying a bowl, a tank, a

standpipe, and a valve comprising upper and lower valve members for admitting water to the standpipe and the tank and closing communication between the tank and bowl or cutting off the flow of water to the standpipe and tank and allowing water to flow therefrom to the bowl, a siphon device having its intake leg connected to the standpipe above the level of the lower valve for discharging residual water from the standpipe following a flushing action.

4. In a flushing or water supply system, a bowl, a standpipe having a water inlet at its lower end and a water outlet at its upper end leading to the bowl, inlet and discharge valves movable in unison and alternately controlling the inlet and outlet, and a siphon device having its intake leg communicating with the pipe above and adjacent to the said inlet valve.

5. In a flushing or water supply system, a bowl having a waste outlet, a standpipe having a water inlet and a drain outlet at its lower end and a water outlet at its upper end leading to the bowl, inlet and discharge valves movable in unison and alternately controlling the inlet and outlet, a drain valve for closing the drain outlet when the inlet is open and opening the drain outlet when the inlet is closed, and a siphon device having its intake leg communicating with the pipe adjacent to the said inlet valve and having the discharge leg independent of connection with the waste outlet of the system.

JOSEPH A. VOGEL.
